GRANULAR MATERIAL SPREADER

Norvin K. Dickerson, Pickens, S. C.

Application December 16, 1933, Serial No. 702,804

1 Claim. (Cl. 275—2)

This invention relates to an improved spreader for loose granular material, especially sand, cracked stone and gravel, such as is used for road construction and surfacing work, and the 5 invention relates in particular to an attachment for dump trucks and corresponding conveyances for such materials.

Under ordinary circumstances in surfacing certain types of highways, it is the practice to coat 10 the traction surface with adhesive tar or asphalt and to thereafter spread loose aggregate, such as gravel, over the tar to adhere thereto. As a general proposition, the gravel is unloaded in piles along the margins of the road and spread 15 by the workmen using shovels. The present invention comprehends an arrangement whereby an even and uniform layer or film of gravel may be spread directly from a moving dumping truck or the like, the truck being moved in a reverse 20 direction and the gravel spread in advance of the rear wheels so as to provide a non-adhesion surface for the unimpeded travel of the truck.

The principal novelty of the invention is predicated upon a novel end-gate in the form of 25 an attachment especially constructed and valved for releasing the gravitating mass of gravel through the instrumentality of manually actuatable mechanical control or valve means.

In reducing the invention to practice and developing the preferred embodiment of the invention, I have evolved and produced a structural assembly which is readily machinable, provided 30 with an easily tripable valve and otherwise mechanically perfected and refined to accomplish 35 the desired results in a highly practicable and satisfying manner.

Other features and advantages will become 40 more readily apparent from the following description and drawings.

In the drawings:—

Figure 1 is a side elevational view showing a 45 fragmentary portion of a motor truck, with the tiltable body in material discharging position and illustrating the adjustable spreader attachment in operative position thereon.

Figure 2 is a top plan view of the attachment, with portions in section.

Figure 3 is a fragmentary perspective view of 50 the regulatory valve unit.

Figure 4 is a detail view of the detachable, interchangeable actuating handle for the rocker shaft.

Figure 5 is a rear end elevational view of the 55 assembly shown in Figure 1.

Figure 6 is a central longitudinal sectional view disclosing the features of construction of the attachment.

Figure 7 is a fragmentary rear end elevation of the hopper-like receiver, with the valve unit removed. 60

Figure 8 is a detail view of the valve unit.

Referring first to Figure 1, it will be observed that the wheel supported chassis of the truck is denoted by the numeral 9 and the hingedly 65 mounted tiltable truck body is indicated at 10. The essential part of the attachment is referred to broadly by the numeral 11. The body of the attachment is somewhat in the nature of a sheet metal hopper-like receiver which is fashioned 70 to function as a spout or chute. It is attachable to the body of the truck at the point where the end gate (not shown) would be arranged. Referring to Figure 6, it will be observed that this hopper or chute embodies a substantially flat 75 bottom 12 formed with an offset attaching lip 13 riveted or otherwise secured to the under side of the bottom of the truck body. This disposes the bottom 12 flush with the bottom of the truck body so as not to obstruct the fluent movement 80 of the gravel (not shown). The vertical end walls 14 of the chute are formed with flanges 15 secured to the side walls of the truck body and this disposes said end walls 14 in substantial longitudinal alignment with said side walls. That 85 side which may be described as the top 16 of the chute is inclined rearwardly and downwardly and terminates in spaced relation above the bottom 12 so as to define a horizontally elongated or substantially rectangular discharge opening or 90 slot 17. The angle irons 18 and 19 secured to the bottom 12 and top 16 are used as reinforcing elements and afford the requisite properties of strength and rigidity.

The regulating valve unit is differentiated by 95 the numeral 20 and is of the construction depicted clearly in Figure 3. It comprises an arcuate valved plate 21 attached by bracing webs 22 to the tubular rocker shaft 23. This entire valve unit is disposed exteriorly of the chute and the extended end portions of the rocker shaft are 100 mounted for oscillation in bearing openings formed in rearwardly projecting suspension brackets 24 carried by said chute. It will be noted that the extended ends of the rocker shaft are 105 apertured, as at 25, to accommodate the tapered end 26 of the detachable, interchangeable lever or handle 27. This permits the handle to be arranged at either end of the rocker shaft so that it may be conveniently grasped by a walking at- 110

tendant. It is to be further observed that the arcuate valve plate 21 is of suitable width to correspond with and completely close the discharge slot 17. Moreover, it is in scraping contact with the upper and lower edges defining said slot. Therefore, said edges have the function of serving as scrapers and said edges being reinforced by the angle irons 18 and 19, provide for dependable self-cleaning action of the convex surface 10 of the valved plate 21.

By having the valve unit 21 exteriorly arranged, it is accessible for easy removal and repair. Moreover, it is visible to the walking attendant so that he may regulate the flow of gravel as 15 conditions require. It is evident too that the flush relationship of the bottom 12 of the chute with respect to the bottom of the truck affords an unobstructed and continuous flow of the gravel through the discharge opening when the truck body 10 is tilted for gravitation of the material. The hopper-like formation of the chute serves to concentrate the material at the point of discharge so that it can be adequately controlled. 20

As before stated, in accordance with the method of operation herein proposed, the truck is moved in a reverse direction and the gravel spills out to form a surfacing layer over which the truck wheels travel, thus laying the traction surface in 25 advance of the rearwardly moving truck and considerably expediting the work of spreading the gravel.

A careful consideration of the foregoing description in conjunction with the invention as 30 illustrated in the drawings will enable the reader to obtain a clear understanding and impression of the alleged features of merit and novelty suf-

ficient to clarify the construction of the invention as hereinafter claimed.

Minor changes in shape, size, materials and re-arrangement of parts may be restored to in actual practice so long as no departure is made 35 from the invention as claimed.

I claim:—

In combination with a vehicle having a dump body, a hopper-like casing connected with the rear end of the body for receiving material from the body when the same is in dumping position, said casing including a flat bottom forming a continuation of the bottom of the body, a pair of end members having their upper edges sloping downwardly and outwardly, and a top member, said top member sloping downwardly and outwardly and having its lower edge spaced from the outer edge of the bottom to provide an elongated outlet opening, reinforcing members connected, one to the lower face of the bottom at the outer end thereof and the other connected to the upper face of the top member at the lower end thereof, said members being flush with the ends of said bottom and top members, outwardly extending plates connected to the outer ends of the end members and forming extensions of the end walls of the outlet opening, a shaft rotatably supported by said plates, with its ends projecting beyond said plates, an arcuate valve plate for controlling the opening, rearwardly extending 100 members connecting the plate with the shaft, and a handle member connected with a projecting end of the shaft for adjusting the valve plate, said plate engaging the reinforced ends of the bottom and upper member during its movement, 105 which acts to remove material sticking to the valve plate.

NORVIN K. DICKERSON.
